UNITED STATES PATENT OFFICE.

WILLIAM E. HILL, OF KALAMAZOO, MICHIGAN.

STEAM-ENGINE.

SPECIFICATION forming part of Letters Patent No. 277,034, dated May 8, 1883.

Application filed August 10, 1882. (No model.)

To all whom it may concern:

Be it known that I, WILLIAM E. HILL, a citizen of the United States, residing at Kalamazoo, county of Kalamazoo, State of Michigan, have invented a new and useful Steam-Engine, of which the following is a specification.

My invention has for its object certain improvements in steam and air feeds for mill-carriages, effecting greater economy, utility, and safety.

Heretofore such devices have been provided with a valve centrally located between the ends of the cylinder, in which the piston is located, necessitating an undue amount of pipe, and causing the steam to become greatly condensed before reaching the cylinder.

In my device I locate a valve at each end of the cylinder, inclosed in a valve-chest having opening immediately into the cylinder at the points where the effect of the steam is most needed. Other novel features are set forth in the following detailed description.

In the drawings forming a part of this specification, Figure 1 is a side elevation of the device complete; Fig. 2, a longitudinal section of the left-hand end of the cylinder on line 22 in Fig. 3; Fig. 3, an end view, looking from the left of Fig. 1; Fig. 4, a bottom view of one end of cylinder; Fig. 5, a valve in perspective, and Fig. 6 a mode of coupling the cylinder.

E is the log-carriage; B, the cylinder, in which is located the piston H, the rod P of which connects at h with said carriage. The rod is provided with a disk or head, H, as shown in Fig. 2.

R R are the valve-chests, located at each end of the cylinder B, each containing a valve, v, connected by the hollow rod or pipe a.

L is a lever for operating the feed, it being connected with the valve-rod a by means of rods e e' and crank-shaft w. A weight, f, is connected with the lower end of lever L by a chain, c', which runs between two friction-wheels, s' s'. By this means said lever is brought to an upright position when released by the operator. The steam-supply pipes from the boiler are connected at t t.

D D is the exhaust-pipe, connecting with each valve-chest, with delivery at u.

e e illustrate the floor of the mill. The valve-chests R R are formed with two ports,

R' z', the former communicating directly with a like port in cylinder B, and the latter connecting with port n' by means of the channel 5: or passage n between the cylinder and chest. The valves v v and valve-rod a are hollow, to admit of the passage of steam or air through them from one chest R to the other. The valve v is provided with a packing-band, s, located 6: in a recess designed for it. A hole, c', communicates from the hollow center of said valve with said band-recess for the purpose of admitting steam or air under said packing to expand it, imparting to it an easy yet effectual engagement with the wall of said chest R. At the back end of valve v a space is left around that part of valve-rod a which plays in the chest R, termed an "exhaust-passage," as it allows the exhaust-steam to pass from 7: the cylinder B to the delivery u.

In the operation, by admitting steam or air, or whatever element is used as a power, into either valve-chest at t, (see Fig. 2, this being the left-hand chest in Fig. 1,) the valve v and its rod a are forced to the right, closing port R' and allowing the steam to enter cylinder B through port z' n' n', which forces the piston H and the carriage E, connected with, it to the right. Of course at the other end of the cylinder the reverse order has taken place in the movement of parts. A portion of the steam has now passed through valves v and valve rod or pipe a to the other valve-chest R without having been detained by any intermediate valve. When piston H moves back, and also the valve, the supply of steam is shut off, as in Fig. 2, and the exhaust-passage R' is opened, bringing the exhaust-space at the rear of the valve v in the proper location to allow the steam to pass down through orifice u. When piston H gets beyond the exhaust-aperture R' toward the end of the cylinder B, whatever steam or air that is in space C becomes closely compressed and acts as a cushion, preventing the piston from moving farther in that direction, thus frequently obviating danger of battering off the end of the cylinder.

Having thus described my invention, what I claim is—

1. A cylinder provided with a piston for connecting with a carriage, and with a supply and exhaust port leading into the valve-chests at each end of said cylinder, and lo-

cated as shown, in combination with valves located in said steam-chests and connected by a hollow rod, all substantially as described and shown.

2. A cylinder provided with a piston, and with a supply and an exhaust port leading into a valve-chest, said ports located in the position to the piston and to the valve and

to each other as set forth, in combination with a valve located in said valve-chest, all substantially as described, whereby the cushion is formed in the end of said cylinder.

WILLIAM E. HILL.
